UNITED STATES PATENT OFFICE.

ELLIOTT S. CHURCH, OF NEWTON, AND FREDERICK J. SHEPARD, JR., OF AUBURNDALE, MASSACHUSETTS.

SHOCK ABSORBER.

Application filed March 20, 1922. Serial No. 545,811.

To all whom it may concern:

Be it known that we, ELLIOTT S. CHURCH and FREDERICK J. SHEPARD, Jr., both citizens of the United States, residing, respectively, 5 at Newton, in the county of Middlesex and State of Massachusetts, and Auburndale, in the county of Middlesex and State of Massachusetts, have invented new and useful Improvements in Shock Absorbers, of which 10 the following is a specification.

This invention relates to shock absorbers particularly intended to check excessive recoil of vehicle springs when the vehicle is in motion and is of that type which makes 15 use of fluid pressure, the flow of which in one direction is more or less restricted, while in the other direction is comparatively free.

The present invention provides a construction by which the extent of restriction of the 20 flow is increased with increased speed of recoil so that the retarding effect is increased, but which acts to decrease the restriction as the speed of recoil decreases so that the recoil 25 is arrested easily and without shock regardless of the degree of roughness of the road being traveled or the extent of flexing movement of the springs, the recoil of which is to be checked.

For a more complete understanding of this 30 invention, together with further objects and advantageous details and combinations of parts, reference may be had to the accompanying drawings in which—

Figure 1 is a side elevation of the device 35 mounted on a vehicle.

Figure 2 is a vertical section on line 2—2 of Figure 3.

Figure 3 is a vertical section on line 3—3 40 of Figure 2.

Figure 4 is a horizontal section on line 4—4 of Figure 3.

Figure 5 is an end elevation with parts removed.

Figure 6 is a sectional perspective of a 45 valve having a valve port therein.

Figure 7 is a perspective partly sectioned of the valve cooperating with the port shown in Figure 6.

Figure 8 is a section on line 8—8 of Figure 2.

Figure 9 is a section on line 9—9 of Figure 2.

Figure 10 is a vertical section showing a 55 different embodiment of the invention.

Figure 11 is a detail of the valve used in the embodiment shown in Figure 10.

Figures 12, 13, 14, and 15 are sections taken on the correspondingly marked lines of Figure 11.

Figure 16 is a view similar to Figure 10 but showing a modification.

Figure 17 is a detail in perspective of a part used in this modification.

Figure 18 is similar to a portion of Figure 2, but on a larger scale.

Referring first to the form shown in Figures 1 to 9 and 18, the device comprises a closed casing 1 having perforated lugs 2 for the passage of securing bolt 3 by which the 70 casing may be made fast to a vehicle body or frame, one member of which is indicated at 4.

The lower portion of the casing 1 is formed as a cylinder 5 within which is reciprocable a piston 6 forming with the cylinder a pressure chamber beneath the piston. As shown this piston comprises a cylindrical portion 7 fitting within the cylinder and having a transverse web 8. This web is 75 formed with a port 9 therethrough with which cooperates a valve 10. Above the web 8 are a pair of aligned perforations for the reception of a pin 12 which may be fixed from rotation therein by means of a transverse key pin 13 (see Figure 3). The pin 12 passes through a bushing 14 carried within a transverse perforation in the lower end of the link 15. The upper end of this link is bifurcated for the reception of a pivot 80 pin 16 by which the link is pivoted to an arm 17 made fast to a rock shaft 18. This rock shaft is journaled in bosses 19 extending inwardly from the upper portion of the casing at one side of the axis of the cylindrical portion 5. At one side of the shaft 18 projects outwardly thereof through a stuffing box 20 of any suitable type for insuring a fluid tight joint between the shaft 18 and this casing.

Outwardly of the stuffing box, shaft 18 has fixed thereto an arm 22 the outer end of which is pivotally connected, preferably by a ball joint to the upper end of a link 23, the lower end of which is connected by a 105 similar ball joint to a member 24 made fast to a vehicle axle 25. This axle is connected to the member 4 of the body or vehicle frame by means of a spring 26 pivoted at its forward end 27 to the member 4 and supported 110

at its rear end by a pivoted link 28 depending therefrom. The particular connection of the spring with the vehicle, however, forms no part of the present invention, any form 5 of mounting of the vehicle from the axle which may be desired being utilized.

With this connection it is evident that on 10 relative up and down motion between the axle and the vehicle, rock shaft 18 is rocked through the arm 17 and link 15, and the piston 6 is reciprocated in the cylinder. The lower end of the cylinder is closed as shown at 30 to form beneath the piston a chamber for the reception of a liquid such as oil or 15 glycerine, but the use of any other fluid such as air or air and oil is within the scope of this invention.

The valve 10 above mentioned seats upwardly against the port 9 to close communication 20 through the piston to the chamber therebeneath. Its valve is normally held in closed position by means of a coiled spring 35 reacting between the lower face of the valve and a flanged ring 36 made fast to the 25 lower end of the piston, this construction being such that on raising the piston within the cylinder, valve 10 is forced from its seat and fluid positioned above the piston is permitted to pass beneath the piston. On 30 downward motion of the piston, however, the valve remains tightly seated and prevents flow of fluid upwardly relatively thereto. To permit the fluid to flow from beneath the piston and restrict it so as to cushion the 35 rebound of the vehicle spring, this valve is shown as provided with a central cylindrical port 40 therethrough. This port leads to the lower end of a sleeve portion 41 extending upwardly from the upper face of the valve 40 and closed off at its upper end. Through the sides of this sleeve portion are a series of 45 openings 42 spaced lengthwise thereof which furnish escape openings for the fluid compressed beneath the piston. Slidable within 50 the valve port is a valve comprising a tubular member 43 which has at an intermediate point an outwardly extending flange 44 which rides in the valve port. This tubular member opens at its upper end within the 55 sleeve 41, the internal diameter of which is smaller than the valve port 40, while the lower end of the tubular member communicates with the space beneath the piston.

In order to vent the space between the 55 flange 44 and the lower edge of the sleeve 41, a series of ports 45 extend through the valve 10 outwardly of the sleeve 41 from the upper end of the valve port. This space is also in communication with the interior of the member 43 by means of an opening 46 extending through the member 43 from a peripheral groove 47. Near the lower end of the member 43 a flanged disk 48 is made fast thereto and a spring 50 seated within the 60 flange of this disk bears at its upper end

against the lower face of the valve 10. This spring normally urges the member 43 downward until the flange 44 contacts and is stopped by a stop ring 51 seated in a groove 52 near the lower end of the valve port. In 70 this position of the parts the openings 42 are uncovered by the reduced end of the valve member 43 so that fluid may flow through the member 43 into sleeve 41 and out through the openings 42, thus furnishing 75 a restricted passage for the fluid.

In case of a descent of the piston the increased pressure therebeneath moves the member 43 upwardly, the pressure reacting against the lower end of the member 43 and the lower surface of the flange 44. This motion of the member 43 causes the openings 42 to be closed progressively, thus additionally restricting the passage of fluid, the amount of such restriction depending on the 80 increase of pressure beneath the piston which is dependent on the speed of descent of the piston. At its limit of upward movement the groove 47 is in alignment with the lower openings 42 while the upper end of member 43 is above the highest opening so that the entire relief for the pressure is through the openings 46 and 45. The greater the speed of such descent, it is evident the greater the pressure developed 85 therebeneath due to the restricted relief for the pressure.

While the amount of restriction to the flow is dependent on the pressure beneath the piston, as above stated, there is also another factor dependent on the speed of the action and more or less independent of the pressure. The passage through the member 43 is so restricted that pressure exerted beneath the piston is not immediately active 100 above this member within the sleeve 42. There is, therefore, on a sudden actuation a momentarily increased pressure acting on the lower end of member 43, uncounterbalanced by equal pressure on its upper end. This uncounterbalanced pressure increases the extent of relative movement of the piston and member 43 to further restrict the flow. If the motion is slow the pressure at both ends of the member 43 is more nearly 105 equal and the pressure acting to move it relative to the piston is more nearly limited in its action to the area of the lower side of the flange 42. This action decreases the effectiveness of the spring 50 in holding the fluid passage as open and free as possible when the rebound action to be cushioned is sudden.

In Figures 10 to 15 is shown a modified construction in which is provided a closed casing 100 having ears 102 by which it may be made fast to the vehicle body and which has therein a fluid pressure cylinder 105. Within this cylinder is mounted a piston 106 to the upper end of which is pivoted a link 107 connected to an arm 108 with a 110

rock shaft 109, this rock shaft passing outwardly of the casing and being connected to the axle for rocking motion similar to the rock shaft 18 of the form first described.

5 The lower end of the cylinder 105 is spaced above the lower end of the casing and has formed therein a port 110. In communication with this port is a sleeve 111 seated within the lower end of the cylinder and cooperating with the upper end of this sleeve is a valve 112. The stem 113 of this valve extends downwardly through a guide member 114 extending across the sleeve 111, and surrounding this stem 114 is a spring 115 reacting against the lower face of the guide 114 and a cover 116 supported on the stem by means of a transverse pin 117. This valve 112 lifts to permit the flow of fluid from the casing 1 into the cylinder 105, but prevents flow in the reverse direction. To permit a restricted flow out from the cylinder a tubular valve or member 120 is provided. The inner end of this valve 120 at 20 121 is slidable through an opening 118 in the side wall of the cylinder, a flange 122 on the portion 121 normally engaging a tubular extension 123 of the cylinder wall. This tubular member 120 has a reduced portion 124 which extends into a cap 125 25 threaded in the outer wall of the casing 1, and communicates at one end with the cylinder 105 beneath the piston and at the other end within the cap 125, while positioned longitudinally thereof a series of openings 126 and smaller openings 127 extend from the central passageway through the side walls thereof.

On outward sliding movement of member 120 these openings 126 and 127 are designed to pass within the sleeve 125 so as to be progressively covered thereby and additionally restrict the passage of fluid outwardly from the cylinder to the interior of the casing. The valve member 120 is normally held with the flange 122 against the tubular portion 123 by means of a spring 130 surrounding valve member 120 and reacting between the flange 122 and the inner end of the plug 125. As shown a spring 135 is positioned within the cylinder 105 and reacts between the valve seat member 111 and the lower face of the piston 106, this spring normally holding the piston in its elevated position. In this construction it is unnecessary to use a rigid link connection between the body and axle of the vehicle as indicated by link 23 in Figure 1, a flexible member such as a strap or cable being used, if desired instead, the spring 135 keeping the strap or cable in taut condition. In this form of the device upward movement of the piston is unrestricted, the valve 112 opening readily to permit flow of fluid into the cylinder therebeneath. The downward motion of the piston is restricted, however, since fluid must

pass through the tubular member 120 and escape from the lateral openings 126 and 127. If the speed of downward movement of the piston is considerable the pressure produced beneath the piston causes the valve member 120 to move outwardly first cutting off the lateral openings 126 and on further motion cutting off serially the lateral openings 127. As shown the openings 126 are of considerably greater area than those shown at 127 so that the rate of restriction to flow is increased rapidly at first and then more slowly as the pressure increases.

In this form of the device also, the small size of the passage through the valve member causes a lag in the building up of pressure against its end within the sleeve 125, so that the pressure within the cylinder caused by sudden movements is more effective in overcoming the tension of spring 130, and moves member 120 further to a more restrictive position, than if the same pressure were applied more gradually. This principle of increasing the effective pressure area on a valve on sudden increase of pressure is regarded as valuable, and as a further illustration its embodiment in a different form of the device is shown in Figures 16 and 17 in which, however, a different principle of obtaining the cushioning or shock absorbing action is employed.

As shown in Figure 16 this device is of the general construction shown in Figure 10, having a piston 1060 slidable in a cylinder 1050, and having a valve member 1200 with a central bore therethrough opening at opposite ends into the lower portion of the cylinder 1050 and into a closed cap 1250 similar to the cap 125 of Figure 10. In this device, however, the relief for the pressure is through a small port 1061 in the piston 1060, a ball valve 1062 being employed to prevent reverse flow into the space beneath the piston 1060. The valve 1200 in this construction permits the relief of pressure beneath the piston when it reaches a desired maximum. For this purpose the central perforation of the member 1200 has one or more lateral openings 1260 extending outwardly therefrom, which, when the valve 1200 is seated against the seat portion 1230 of the pressure cylinder, are closed off by the walls of this seat. The valve 1200 is normally held in seated position by means of a spring 1300 reacting between the inner end of the plug 1250, and the flange 1220 of the valve. On sufficient pressure being exerted within the cylinder the tension of the spring 1300 is overcome and the member 1200 is pushed into the cap 1250, thus opening the passages 1260, and permitting the escape of fluid from within the cylinder. The passage through the member 1200 is so restricted that on sudden increase of pressure within the cylinder there is a lag in

the building up of pressure within the cap 1250 so that the effective area exposed to pressure from the pressure cylinder approaches more nearly the area of the exposed end of the member 1200. If the building up of pressure is slow, however, the pressure builds up within the cap 1250 and partially balances the pressure within the cylinder so as to cause the spring 1300 to be more effective in holding the valve seated. This method of operation automatically compensates for changes in condition of the fluid, such as oil, due to change in temperature. For example, when the weather is cold and the fluid is sluggish the time required to build up the pressure within the cap 1250 is considerably longer than in warm weather when the fluid flows freely, so that a less sudden and extensive pressure within the cylinder is sufficient to open the relief valve. Under such conditions also the relief of the pressure through the port 1061 is less so that an earlier actuation of the relief valve is desirable. In this form of the device there is no graduated modification of the extent of restriction to the flow depending on the pressure within the pressure cylinder or the speed of the pressure movement of the piston except when the pressure is excessive. It does, however, make use of the delayed transmission of pressure through a restricted passage in order to modify the normal action of the device at certain times.

It is evident, of course, that the openings 42 shown in the first form of the mechanism may progressively decrease in size or be more restricted in number lengthwise of the sleeve in order to impart a variable increase of resistance to the flow of fluid with the decrease or increase of pressure beneath the piston and consequently of speed of recoil.

Having thus described certain embodiments of this invention it should be evident to those skilled in the art that many changes and modifications might be made therein without departing from the spirit or scope of the appended claims.

We claim:

1. In a shock absorber, a pair of relatively movable members adapted to be interposed between the body and axle of a vehicle, means permitting said members to move freely relatively in one direction, and means interposing a resistance to the relative movement of said members in the opposite direction depending in extent directly on the speed of relative movement of said members.
2. A shock absorber comprising a cylinder, a piston movable in said cylinder, means permitting the flow of fluid to said cylinder beneath said piston but preventing flow in the reverse direction, and means responsive to increasing and decreasing pressure beneath

said piston for interposing increasing and decreasing resistances, respectively, to the passage of fluid pressure from beneath said piston.

3. In a shock absorber, a pair of members 70 comprising a cylinder and a piston in said cylinder, said members being constructed to be interposed between a vehicle body and axle, a pair of ports communicating with said cylinder, a valve in one of said ports 75 permitting flow through said port freely in one direction and closing against flow in the opposite direction, and a valve in said other port permitting restricted flow when said first port is closed, the extent of restriction being variable and increasing with increased pressure of fluid thereagainst.

4. In a shock absorber, a cylinder, a piston movable in said cylinder, means for connecting said piston and cylinder intermediate a vehicle body and axle, a pair of ports communicating with said cylinder beneath said piston, a valve in one of said ports permitting free flow to said cylinder beneath said piston but closing to prevent escape of fluid 80 therefrom, a tubular valve slidable through the other of said ports, a guide sleeve having its outer end closed for guiding said tubular valve and into which the tubular portion opens, said guide sleeve having a series of 85 openings through its side wall spaced lengthwise thereof, and a spring normally holding said tubular valve inwardly toward said cylinder, whereby said tubular valve normally uncovers the maximum number of 90 said openings, but is movable under increased pressure beneath said piston to progressively close said openings to interpose increased resistance to the passage of fluid.

5. In a shock absorber, a cylinder, a piston movable in said cylinder, means for connecting said piston and cylinder intermediate a vehicle body and axle, a port communicating with said cylinder beneath said piston, a tubular valve slidable in said port and having a portion of reduced diameter, a sleeve having its outer end closed for closely guiding the outer end of said sleeve portion and into which fluid may flow through said valve, said sleeve having a series of openings 115 spaced longitudinally thereof for the escape of fluid therefrom and adapted to be closed serially by movement of said reduced portion into said sleeve, a spring urging said reduced portion outwardly from said sleeve, and means permitting ready flow into said cylinder beneath said piston.

6. In a shock absorber comprising a cylinder, a piston movable in said cylinder, and means for connecting said piston and cylinder intermediate a vehicle body and axle, the combination of a pair of ports communicating with said cylinder beneath said piston, a valve in one of said ports permitting free flow to said cylinder beneath said 120 125 130

piston but closing to prevent escape of fluid therefrom, a tubular valve slideable through the other of said ports, a guide sleeve having its outer end closed for guiding said tubular valve and into which the tubular portion opens, said guide sleeve having a series of openings throughout its side wall spaced lengthwise thereof, said openings being of preferably greater area toward one end of 10 said sleeve than at the other, and a spring normally holding said tubular valve toward said cylinder, whereby said tubular valve normally uncovers the maximum number of said openings but is movable under increased 15 pressure to interpose a resistance to the passage of fluid increasing at a different rate than the increase of pressure beneath said piston.

7. In a shock absorber comprising a cylinder, a piston movable in said cylinder, and means for connecting said piston and cylinder intermediate a vehicle body and axle, the combination of a port through said piston, a valve for said port permitting 20 ready flow of fluid into said cylinder beneath said piston and preventing flow in the reverse direction, said valve having a port therethrough and a sleeve portion closed at its outer end and having openings 25 spaced longitudinally thereof and in communication with said valve port, a tubular valve slideable in said valve port and sleeve and opening at opposite ends into said cylinder beneath said piston and into said 30 sleeve and slideable in said sleeve to cover or uncover more or less of said sleeve openings, and a spring normally holding said tubular valve in a position to uncover said openings.

8. In a shock absorber comprising a cylinder, a piston movable in said cylinder, and means for connecting said piston and cylinder intermediate a vehicle body and axle, the combination of a port through said piston, a valve cooperating with said port to 40 prevent flow of fluid from said cylinder beneath said piston but permitting flow in the reverse direction, a port through said valve, a tubular member carried by said valve slidably in said valve port, a sleeve closed at one 45 end and fixed at its other end to said valve and having openings through its side spaced longitudinally thereof, said tubular member

extending within said sleeve and closing off more or less of said openings by sliding in 55 said valve port, a spring reacting between said piston and valve to urge said valve closed, and a spring reacting between said valve and member to normally maintain said opening uncovered.

9. In a shock absorber, a cylinder, a piston 60 movable in said cylinder, a pair of ports communicating with the space beneath said piston, a valve in one of said ports opening to permit flow inward beneath said piston and closing to prevent outflow, a valve member 65 for controlling the other of said ports and having a perforation therethrough opening at one end into the space beneath said piston, a sleeve member closed off at one end and slidably receiving said valve 70 member, the opposite end of said perforation opening into said sleeve, and a spring urging said valve member from said sleeve member, one of said members having lateral escape perforations serially closed by movement of said valve member against the force 75 of said spring to effect a variable restricted passage for the escape of pressure from beneath said piston through the perforation of said valve member.

10. In a shock absorber, a cylinder, a piston in said cylinder, an outlet for pressure in said cylinder beneath said piston, a valve for controlling said outlet, said valve having a constricted passage therethrough 80 in communication with the space beneath said piston, a chamber into which said valve extends and with the interior of which said passage communicates, and a spring urging 85 said valve into seating engagement with said outlet.

11. In a shock absorber, a pressure chamber for the reception of a fluid, an outlet for said chamber, a valve subjected to pressure from said chamber for controlling said outlet, a spring urging said valve in opposition to said pressure, and means acting to increase the effective area of said valve subjected to pressure on sudden increases of pressure in said chamber.

In testimony whereof we have affixed our signatures.

ELLIOTT S. CHURCH.
FREDERICK J. SHEPARD, JR.
